[57] CLAIM

The ornamental design for a post and beam connector,
as shown.

DESCRIPTION

FIG. 1 is a perspective view of a post and beam connector showing my new design;

FIG. 2 is a rear elevational view thereof;

FIG. 3 is a left side elevational view thereof;

FIG. 4 is a top plan view thereof;

FIG. 5 is a right side elevational view thereof;

FIG. 6 is a bottom plan view thereof;

FIG. 7 is a perspective view of a second embodiment of
FIG. 1;

FIG. 8 is a rear elevational view thereof;

FIG. 9 is a left side elevational view thereof;

FIG. 10 is a top plan view thereof;

FIG. 11 is a right side elevational view thereof;

FIG. 12 is a bottom plan view thereof;

FIG. 13 is a perspective view of a third embodiment of
FIG. 1;

FIG. 14 is a rear elevational view thereof;

FIG. 15 is a left side elevational view thereof;

FIG. 16 is a top plan view thereof;

FIG. 17 is a right side elevational view thereof; and

FIG. 18 is a bottom plan view thereof.
